2 SHEETS—SHEET 2.

UNITED STATES PATENT OFFICE.

EDWARD M. THALHEIMER, OF PHILADELPHIA, PENNSYLVANIA.

BALL-CONDUCTING DEVICE FOR POOL-TABLES.

1,257,050.

Specification of Letters Patent. Patented Feb. 19, 1918.

Application filed August 10, 1917. Serial No. 185,438.

To all whom it may concern:

Be it known that I, EDWARD M. THALHEIMER, a citizen of the United States, residing at Philadelphia, in the county of 5 Philadelphia and State of Pennsylvania, have invented certain new and useful Improvements in Ball-Conducting Devices for Pool-Tables, of which the following is a specification.

10 My invention consists of an improved ball-conducting device for pool tables. One object of my invention is to provide a device of the above mentioned character which can be easily and quickly attached to pool 15 tables of various types and which will serve to conduct the balls, after they have been shot into the pockets, to a common receptacle located at one end of the table.

Another object is to so make my invention 20 that it can be attached to a table without material change in the construction of the latter.

A further object is to so construct my invention that it can be manufactured and 25 sold at a reasonably low price.

These objects, and other advantageous ends which will be described hereinafter, I attain in the following manner, reference being had to the accompanying drawings in 30 which—

Figure 1 is a top plan view of a pool table having my invention thereon.

Fig. 2 is a side elevation of Fig. 1.

Fig. 3 is an elevation of one end of the 35 table shown in Fig. 1.

Fig. 4 is an elevation of the other end of the table.

Fig. 5 is an enlarged fragmentary section taken on the line 5—5 of Fig. 2.

Fig. 6 is an enlarged section taken on the 40 line 6—6 of Fig. 3.

Fig. 7 is an enlarged sectional plan taken on the line 7—7 of Fig. 3.

Fig. 8 is an enlarged sectional plan of a 45 portion of a ball-conducting trough which forms a part of my invention and taken on the line 8—8 of Fig. 4.

Fig. 9 is a perspective view of the portion 50 of my invention shown in Fig. 8.

Fig. 10 is a fragmentary plan of a modified form of a portion of my invention.

Referring to Figs. 1 to 9 inclusive of the drawing, 1 represents a pool table having side pockets 2 and 3, and corner pockets 55 4, 5, 6, and 7. The base 8 of the table, at its sides and ends, is provided with the usual

securing bolts 9, and I preferably use these same bolts as a means for securing my invention to the table.

My invention, as illustrated, consists primarily of a trough 10, preferably made of sheet material such as metal or compressed fiber and positioned under the ledge 11 of the table. The trough, as illustrated, is made in sections, each section having a gutter 12 formed at its bottom, and an upwardly extending flange 13, the latter being provided with bolt holes through which the bolts 9 extend and thereby secure the trough to the table.

Each side of the table has two trough sections 14 and 15 secured thereto. These sections have bulged portions 16 and 17 respectively which are directly under the side pockets 2 and 3, and at their tops conform to the shape of the side pocket irons 18. Furthermore, these bulged portions preferably overlap each other as clearly shown in Figs. 1 and 2.

Bulged portions 16 and 17 taper toward 80 their bottom and blend with the curvature of the gutter 12 (see Figs. 2 and 5). The sections 14 have corner pieces 20 riveted thereto as clearly shown in Figs. 2, 4, 8, and 9, these corner pieces being positioned respectively under the corner pockets 4 and 6, so that balls which are shot into either of these pockets, will drop through the corner pieces into the gutters 12 of the sections 14, it being noted that each of said gutters has 90 an extension 21 which projects into the corner piece and forms a bottom therefor in conjunction with the bottom 22 of the corner piece.

The ends 23 of the gutters 12 of the sections 14 are preferably beveled as illustrated in Figs. 8 and 9, and the edges 24 of the corner pieces 20 are also beveled so that a ball dropping through the corner pockets 4 and 6, will roll over the parting between 95 100 the beveled edges 23 and 24, but any dirt dropping into said pockets will find its way out through the space 25 between the edges 23 and 24.

The sections 14 and 15 of the trough 105 have their gutters positioned at a slant from said corner pockets 4 and 6 toward the corner pockets 5 and 7, so that balls dropping either through the corner pockets 4 and 6 or side pockets 2 and 3 will roll toward the 110 end of the table including the corner pockets 5 and 7. The sections 15 of the trough

also have corner pieces 26 which are riveted thereto as illustrated at 27, and these corner pieces 26 are also riveted to short sections 28 of the trough which are positioned 5 under the ledge 11 at the end 29 of the table (see Figs. 3 and 7).

The ends 30 of the sections 15, and the ends 31 of the sections 28, are also beveled in the same manner as the edges 23 and 24 10 above described, so that openings 32 are provided directly below the pockets 5 and 7 to prevent the collection of dirt within the trough.

A box 33 is suspended on hooks 35 at the 15 end 29 of the table, and the ends 34 of the sections 28 are open and so positioned that the balls as they roll therethrough will drop into the box 33.

A slideable bottom 36 is provided on the 20 box 33, so that by manually moving said bottom, the balls collected within the box can be permitted to drop into a basket held thereunder, or if desired, the entire box can be removed by raising it from the hooks 35, 25 so that the balls can be replaced upon the table.

It will be noted that the gutter portions of the sections 28 slant downwardly from the pockets 5 and 7 toward their ends 34, so 30 that the balls after dropping through any of the pockets, will eventually find their way into the box 33.

In the form of my invention shown in Fig. 10, instead of having the corner pieces made 35 separately as for example the corner pieces 26, I have illustrated an instance where the ends of the sections can be overlapped as shown at 37 and riveted.

From the above description, it will be 40 noted that my invention can be applied to pool tables of various types without changing the construction of the table in any manner, it merely being necessary to remove the nuts on the bolts 9 so that the holes in 45 the flanges 13 can register with the bolts, and by again applying the nuts, the device will be securely held in place.

While I have described my invention as taking a particular form, it will be understood 50 that the various parts of my invention may be changed without departing from the spirit thereof, and hence I do not limit myself to the precise construction

set forth, but consider that I am at liberty to make such changes and alterations as fairly come within the scope of the appended claims.

Having thus described my invention, what I claim as new and desire to secure by Letters Patent is:

1. A ball-conducting device for a pool table including a trough having a gutter portion designed to be positioned below the pockets of the table, said trough having a flange projecting from said gutter and adapted to be secured to the table and to extend across the sides of the openings which form said pockets, substantially as described.

2. A ball-conducting device for a pool 70 table including a trough made in sections, said sections having gutter portions adapted to extend under the side and corner pockets of said table, said sections including flanges projecting from the respective gutter 75 portions, said flanges having oulged portions to correspond with the contour of the side pockets, substantially as described.

3. A ball-conducting device for a pool 80 table including a trough made in sections, said sections having gutter portions adapted to extend under the side and corner pockets of said table, said sections including flanges projecting from the respective gutter 85 portions, and corner pieces secured to certain of the sections below the corner pockets of the table, substantially as described.

4. A ball-conducting device for a pool 90 table including a trough made in sections, said sections having gutter portions adapted to extend under the side and corner pockets of said table, said sections including flanges projecting from the respective gutter 95 portions, the gutter portions below the corner pockets at their bottoms having beveled edges positioned adjacent each other to form corner turns in the gutter, substantially as described.

In testimony whereof I have signed my 100 name to this specification in the presence of two subscribing witnesses.

EDWARD M. THALHEIMER.
